(57) **ABSTRACT**

A new *fuchsia* plant particularly distinguished by flowers having white petals and red sepals, a compact, upright plant habit, and a freely-branching growth habit, is disclosed.

1 Drawing Sheet

1

Genus and species: *Fuchsia* sp.
Variety denomination: 'KLEFU14840'.

BACKGROUND OF THE NEW PLANT

The present invention comprises a new and distinct variety of *fuchsia*, botanically known as *Fuchsia* sp. and hereinafter referred to by the variety name 'KLEFU14840'. 'KLEFU14840' originated from a controlled-cross in October 2011 between the proprietary female *fuchsia* variety '2010.15' (unpatented) and the proprietary male *fuchsia* variety '2010.7' (unpatented).

In March 2011, the two *fuchsia* parental lines '2010.15' and '2010.7' were crossed in Stuttgart, Germany and seeds were obtained. The seeds were sown and plants were grown for evaluation. A plant line was selected in March 2012 and subsequently named 'KLEFU14840'. In March 2012, 'KLEFU14840' was first vegetatively propagated by vegetative cuttings in Stuttgart, Germany. 'KLEFU14840' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

1. Flowers having white petals and red sepals;
2. A compact, upright plant habit; and
3. A freely-branching growth habit.

DESCRIPTION OF THE PHOTOGRAPH

This new *fuchsia* plant is illustrated by the accompanying photograph which shows an overall view of the plant. The

2

photograph is of an approximately 3-month-old plant grown in Stuttgart, Germany under greenhouse conditions in May 2014.

The colors shown are as true as can be reasonably obtained by conventional photographic procedures.

DESCRIPTION OF THE NEW VARIETY

The following detailed descriptions set forth the distinctive characteristics of 'KLEFU14840'. The data which define these characteristics were collected from asexual reproductions carried out in Latina, Italy. Data was collected on 2.5 to 3 month-old plants in Latina, Italy grown in a greenhouse in June 2015. Color references are to The R.H.S. Colour Chart of The Royal Horticultural Society of London (R.H.S.), 5th edition (2007).

Classification:

Family.—Onagraceae.

Botanical.—*Fuchsia* sp.

Designation.—'KLEFU14840'.

Parentage:

Female parent.—The proprietary female *fuchsia* variety '2010.15' (unpatented).

Male parent.—The proprietary male *fuchsia* variety '2010.7' (unpatented).

Propagation:

Type.—Vegetative cuttings.

Time to initiate roots, summer.—About 1 to 2 weeks at 20° C. to 25° C.

Time to initiate roots, winter.—About 2 weeks at temperatures of 18° C. to 22° C.

Time to produce a rooted young plant, summer.—3 to 4 weeks at temperatures of 20° C. to 25° C.

Time to produce a rooted young plant, winter.—4 weeks at temperatures of 18° C. to 22° C.

<i>Root description.</i> —Fine, fibrous, yellowish-white in color.	5	<i>Shape.</i> —Obovate.	
<i>Rooting habit.</i> —Freely branching; medium density.		<i>Apex.</i> —Obtuse.	
Plant:		<i>Base.</i> —Cuneate.	
<i>Plant habit/form.</i> —Compact, upright plant habit.	5	<i>Margin.</i> —Entire.	
<i>Growth habit.</i> —Freely-branching habit with lateral branches developing potentially at every node; bushy plant habit; vigorous growth habit.		<i>Texture (both upper and lower surfaces).</i> —Smooth, glabrous, satiny.	
<i>Plant height.</i> —18.0 cm to 20.0 cm.	10	<i>Color.</i> —Upper (outside) surface: When opening: RHS 155A; veins RHS N57B (Red-Purple). Fully open: RHS 155A; veins RHS N57B (Red-Purple). Lower (inside) surface: When opening: RHS 155A; veins RHS N57B (Red-Purple). Fully open: RHS 155A; veins RHS N57B (Red-Purple).	
<i>Plant diameter.</i> —25.0 cm to 28.0 cm.			
Lateral branches:		<i>Sepals:</i>	
<i>Length.</i> —Approximately 15.0 cm.		<i>Arrangement.</i> —Calyx star-shaped with four sepals fused at the base.	
<i>Diameter.</i> —Approximately 2.0 mm.		<i>Length.</i> —Approximately 2.7 cm.	
<i>Internode length.</i> —Approximately 2.5 cm.	15	<i>Width.</i> —Approximately 0.9 cm.	
<i>Strength.</i> —Strong, flexible.		<i>Shape.</i> —Elliptic.	
<i>Aspect.</i> —Upright to semi-upright, compact.		<i>Apex.</i> —Slightly cuspidate.	
<i>Texture.</i> —Pubescent.		<i>Base.</i> —Attenuate, fused.	
<i>Color.</i> —Close to RHS 146B and lightly tinted with close to RHS 187B.	20	<i>Margin.</i> —Entire.	
Leaves:		<i>Texture (both upper and lower surfaces).</i> —Smooth, glabrous, and satiny.	
<i>Arrangement.</i> —Opposite, simple.		<i>Color.</i> —Upper (outside) surface: When opening: RHS 51A. Fully opened: RHS 52A. Lower (inside) surface: When opening: RHS 58B. Fully opened: RHS 58C.	
<i>Length.</i> —4.4 cm on average.			
<i>Width.</i> —1.65 cm on average.		30 <i>Peduncles:</i>	
<i>Shape.</i> —Ovate.	25	<i>Length.</i> —3.0 cm on average.	
<i>Apex.</i> —Broadly acute.		<i>Diameter.</i> —0.1 cm.	
<i>Base.</i> —Obtuse/rounded.		<i>Angle.</i> —Arching.	
<i>Margin.</i> —Shallowly serrate.		<i>Strength.</i> —Moderately strong.	
<i>Texture (both upper and lower surfaces).</i> —Glabrous.		<i>Texture.</i> —Sparsely pubescent.	
<i>Venation pattern.</i> —Pinnate; arcuate.		<i>Color.</i> —RHS 144A.	
<i>Venation color.</i> —Upper surface: Close to RHS 146B. Lower surface: Close to RHS 147C.	35	Reproductive organs:	
<i>Color.</i> —Developing leaves: Upper surface: Close to RHS N137B. Lower surface: Close to RHS 137B. Fully expanded leaves: Upper surface: RHS N137B. Lower surface: RHS 147B.		<i>Stamens.</i> —Quantity per flower: 8. Anther shape: Ellipsoidal. Anther size: About 2.0 mm by 1.0 mm. Anther color: RHS 158A with RHS N57B (Red-Purple) shading. Pollen amount: Scarce. Pollen color: Close to RHS 155A.	
Petiole:		<i>Pistils.</i> —Quantity: 1 per flower. Pistil length: 3.5 cm on average. Style color: Towards the base, close to RHS 155D; towards the apex, close to RHS 54A. Stigma shape: Clavate. Stigma color: RHS 49A. Ovary color: RHS 144A.	
<i>Length.</i> —1.4 cm on average.			
<i>Diameter.</i> —1.5 mm on average.			
<i>Texture.</i> —Upper surface: Smooth, glabrous, concave. Lower surface: Smooth, glabrous, convex.	40		
<i>Color.</i> —Upper surface: RHS 144B. Lower surface: RHS 144C.			
Flower:			
<i>Flower arrangement and habit.</i> —Single axillary flowers; flowers pendulous; freely flowering habit with potentially two flowers per leaf axil.	45		
<i>Total number of flowers per plant.</i> —Over 40 fully open flowers and 80 buds on a mature plant when at flowering stage.			
<i>Fragrance.</i> —None detected.			
<i>Natural flowering season.</i> —Long flowering period; in Europe, plants flower from early spring to autumn; flowering continuous during this period.			
<i>Flower longevity.</i> —Flowers last about four to six days on the plant.	55		
<i>Flower diameter.</i> —1.0 cm (petals), 4.5 cm (sepals).			
<i>Flower height (depth).</i> —Approximately 3.6 cm (base of sepals to stigma tip).			
<i>Flower buds.</i> —Shape: Elliptic. Length: Approximately 2.6 cm. Diameter: Approximately 1.2 cm. Color: RHS 51A.	60		
Petals:			
<i>Arrangement.</i> —Typically four in a single whorl.			
<i>Length.</i> —Approximately 1.5 cm.			
<i>Width.</i> —Approximately 1.2 cm.	65		
		‘KLEFU14840’ is distinguished from its parents as described in Table 1:	
		COMPARISON WITH PARENTAL LINES AND KNOWN VARIETY	
		TABLE 1	
		Comparison with Parental Lines	
Trait	‘KLEFU14840’	Female parent ‘2010.15’	Male parent ‘2010.7’
Plant height	Shorter than ‘2010.15’ and ‘2010.7’	Medium	Medium

US PP27,993 P3

5

TABLE 1-continued

Comparison with Parental Lines			
Trait	'KLEFU14840'	Female parent '2010.15'	Male parent '2010.7'
Flower size	Smaller than '2010.15' and '2010.7'	Medium	Medium

'KLEFU14840' can be compared to the commercial variety Diva Red White (patent status unknown). Differences between the two varieties are described in Table 2:

6

TABLE 2

Comparison with Similar Variety			
5	Trait	'KLEFU14840'	Commercial line Diva Red White
	Plant height	Shorter than Diva Red White	Medium

We claim:

- 10 1. A new and distinct variety of *fuchsia* plant named 'KLEFU14840' as illustrated and described herein.
